(57) **CLAIM**

The ornamental design for a ladder buffer, as shown and described.

DESCRIPTION

FIG. 1 is a front top perspective view of a ladder buffer showing my new design.

FIG. 2 is a bottom rear perspective view thereof.

FIG. 3 is a front elevation view thereof.

FIG. 4 is a rear elevation view thereof.

FIG. 5 is a right side elevation view thereof.

FIG. 6 is a left side elevation view thereof.

FIG. 7 is a top plan view thereof.

FIG. 8 is rear plan view thereof; and,

FIG. 9 is an illustrative front bottom perspective in a use configuration with a ladder.

The broken lines shown in the figures are for the purpose of illustrating environment and form no part of the claimed design.
